UNITED STATES PATENT OFFICE.

PAUL A. STOVER, OF RACINE, WISCONSIN, ASSIGNOR TO THE STOVER SIGNAL ENGINEERING CO., OF RACINE, WISCONSIN, A CORPORATION OF DELAWARE.

DESIGN FOR AN AUTOMOBILE SIGNAL-LAMP COVER.

Application filed December 31, 1925. Serial No. 15,911. Term of patent 14 years.

To all whom it may concern:

Be it known that I, PAUL A. STOVER, a citizen of the United States, residing at Racine, in the county of Racine and State of Wisconsin, have invented a new, original, and ornamental Design for Automobile Signal-Lamp Cover, of which the following is a specification, reference being made to the

drawing, forming a part thereof, in which—

Fig. 1 is a front elevation of my automobile signal lamp cover, and Fig. 2 is a side elevation of the cover.

I claim:

The ornamental design for an automobile signal lamp cover substantially as shown.

PAUL A. STOVER.
